ELECTRICAL ACCUMULATOR

James W. Bryce, Glen Ridge, N. J., assignor to
 International Business Machines Corporation,
 New York, N. Y., a corporation of New York

Application June 21, 1938, Serial No. 214,930

4 Claims. (Cl. 235—61.6)

This invention relates to record controlled accounting machines and more particularly to value registering or accumulating mechanism used in such machines.

The principal object of the present invention resides in the provision of a unique accumulator of the strictly electrical type applicable to a record-controlled accounting machine with a view toward simplification and improved arrangement of the controlling circuit.

More specifically, the invention contemplates the provision of an accounting machine with accumulating means comprising a plurality of ordinal series of value-corresponding relays, each value relay having a controlling relay companion thereto; the provision of novel means for effecting successive energization of an entry circuit to each series of companion relays so as to energize a plurality of said relays successively according to the value entered in that series; the provision of means to maintain each of the energized value relays in its operated condition until a predetermined number of said relays have been energized, each value relay, upon being energized, conditioning the controlling relay of the next higher ordinal value position for operation upon the next energization of the entry circuits; and the provision of transfer means controlled by zero value position of one ordinal series of relays to enter one into the next higher ordinal series of relays as the relay progression in the one series passes from said highest ordinal value position to the zero position.

According to the invention, the accumulator comprises a series of sets of companion relays in each order adapted to be energized successively according to multiple impulses representing differential values entered therein. Each set of relays, representing an ordinal value or digit position, comprises a control relay and a companion value relay, the sequence of energization being such that, upon entry of an impulse, the control relay is first energized and this in turn causes its companion value relay to become energized. The value relay, immediately upon becoming energized, effects the deenergization of the operated control relay, and concurrently conditions the control relay of the next higher set in the series for operation upon entry of the next impulse. Succeeding impulses cause similar operations of further sets of relays in the series, and the value relays thus energized are maintained in their operated condition until a predetermined ordinal value position is reached, at which time the maintaining circuit to all value

relays except the one in the predetermined position is broken. An electrical carry means is utilized to enter a carry impulse in the next higher orders of the accumulator as the relay progression in lower orders passes from the highest digit position to the zero position. The accumulator performs subtraction by the entry of a number of impulses complementary to the value of the digit to be subtracted. A simple read-out means is provided and operates under the control of the last-operated relay to complete circuits to print magnets on total taking cycles.

Other objects of the invention will be pointed out in the following description and claims and illustrated in the accompanying drawings, which disclose, by way of example the principle of the invention and the best mode, which has been contemplated, of applying that principle.

In the drawings:

20 Fig. 1 is a sectional view of the card feeding and analyzing mechanism of an accounting machine showing the essential operating parts.

25 Figs. 2, 2a and 2b together comprise a representative circuit diagram of the machine.

Fig. 3 shows an electrical timing chart of the machine.

Fig. 4 shows an enlarged complete view of the relay arrangement of the units order of the accumulator.

30 For purposes of illustration, the accumulator forming the subject matter of the present invention will be described as applied to an accounting machine of the type shown in the U. S. Patent 1,976,617 issued to Lake et al. on Oct. 9, 1934.

35 A brief description of the card feeding and analyzing mechanism of the machine and the general machine operating circuits will now be set forth followed by a detailed description of the accumulator. If more detailed explanation of the various parts of the machine other than the accumulator is desired, reference should be made to the aforementioned Lake patent.

Card feeding and analyzing mechanism

45 The record cards C (Fig. 1) are placed in a card handling section generally designated 10 from which they are fed downwardly, one by one, by picker 11, so that the leading edge is moved into cooperation with a pair of feed rollers 12, 50 after which the card is fed past successive pairs of feed rolls 13, 14 and 15 to a stacker (not shown).

Between pairs of feed rollers 12 and 13 are located the upper analyzing brushes UB, and between rollers 14 and 15 are located lower an-

alyzing brushes LB. These sets of brushes cooperate with contact rolls 16 and 17 respectively. At each of the brush stations is a pivoted card lever, the one at the upper brush station cooperating with a pair of contacts 18 and the one at the lower brush station cooperating with a pair of contacts 19. The levers serve to close their respective contacts while the record card is passing the brushes and permit the contacts to open during the interval between cards.

On the first feed cycle of the machine, the leading card will be moved downwardly to a position where the leading edge of the card will have slightly passed the upper brushes UB, insulating them from the contact roll 16. During the second cycle, the card will be advanced by the feed rollers past the upper brushes to an exactly similar position with respect to the lower brushes LB, insulating them from the contact roll 17. Meanwhile, during this second cycle, a second card will have been advanced to the upper brushes so that there is now a card under the upper brushes and lower brushes. At this time both card levers are operated, and their associated contacts 18 and 19 closed. During the third cycle, the cards will pass the lower and upper brushes respectively and corresponding index point positions will be analyzed concurrently by the two sets of brushes. At the end of the third cycle, the first card will have been passed down beyond the lower brushes, the second card will have advanced into a position where its leading edge insulates the lower brushes from their contact roll 17, and a third card will have been fed into a similar position with respect to the upper brushes.

Value designations on the record cards are analyzed by the lower brushes LB which cause corresponding entries to be made into accumulators for the purpose of ascertaining totals. The upper brushes UB function in conjunction with the lower brushes LB under group control operation, which will be explained later in detail, to allow the cards to continue to feed as long as control designations representing a group are the same on successive cards. At the end of a cycle during which the control designations analyzed by the upper and lower brushes differ, the feeding mechanism is automatically stopped. Totals for the group may then be taken from the accumulators in which entries were made.

When certain cards have amounts to be added and others have amounts to be subtracted, the upper brushes are employed in distinguishing one type from the other by the so-called "X" selection method. In this method, provision may be made so that subtract cards, for example, carry an "X" designation and the add cards do not. The "X" designation may be placed in any column of the card, and is located one index position above the "O" position in that column. Upon the sensing of the "X" designation by the upper brush in the corresponding column, circuits will be established so that during the next cycle as the amounts on the "X" card are analyzed by the lower brushes these amounts will be subtractively entered into the accumulators. The amounts from "no X" cards are additively entered into the accumulators by the normal entry circuits.

Further explanation of the functions of the card feed and analyzing mechanism, except as set forth later in connection with a description of the circuits of the machine, is deemed unnecessary. If a more detailed description is

desired, it may be obtained by referring to the aforementioned U. S. Patent 1,976,617.

General machine circuits

The circuits of the machine may be connected to a source of current through a switch S indicated in the upper left hand corner of Fig. 2. With the switch S closed, current is supplied to main lines 30 and 31, which through wires 32 and 33 connect these lines to the input side of a dynamotor indicated at DY. The output side of the dynamotor is connected to wires 34 and 35 which supply current to the machine proper. The use of the dynamotor DY permits the operation of the tabulating machine from a source of current whose potential is different than that for which the various electrical devices of the machine are adapted. Specifically, if the source of current is 220 volts D. C., the dynamotor, when wired as shown, will impress current of 110 volts D. C. on the lines 34 and 35. If the supply of current is 110 volts, then, of course, the dynamotor may be dispensed with and direct connection made between lines 30 and 34 and lines 31 and 35 as indicated by dotted lines. When current is initially supplied to the dynamotor, the current through the input armature thereof will pass through a resistance 36 in parallel with which are wired contacts 37a of a relay magnet 37. Magnet 37 is directly connected across the output lines 34 and 35 of the dynamotor and close as soon as the voltage delivered is sufficient to operate the relay. Contacts 37a close to shunt out the resistance 36 and permit the full input current to be applied to the input armature of the dynamotor.

In tabulating machines of this class, it is customary to first send the machine through a reset cycle of operations to insure that the accumulating devices are clear and also to set up the automatic control mechanism. These resetting operations will be more fully explained later. Suffice it to say at the present time, however, that during the resetting operations, motor control relay magnet 38 is energized and a holding circuit provided for maintaining it energized until change. Contacts 38a of this relay will therefore be closed and the contacts 38b opened.

The machine is now ready to start card feeding operations after cards have been placed in the feed magazine 10. Depression of the start key to close contacts ST will complete a circuit as follows: from line 34, closed cam contacts P1, tabulating clutch magnet 29, contacts 29a, start relay 39, start key contacts ST, stop key contacts SP, closed relay contacts 38a, to line 35. Energization of magnet 29 causes opening of the contacts 29a and the circuit will now include relay magnet 40, which is wired in parallel with the contacts 29a.

Magnet 40 will close its contacts 40a to complete a circuit through the tabulating motor TM as follows: from line 30, motor TM, contacts 40a, to line 31, thus initiating the operation of the motor. Motor TM is of the two-speed type having a resistance 41 connected in series with its field winding. Shunted across the resistance 41 are the contacts 28 which may be arbitrarily closed to shunt out the resistance 41 and cause the motor TM to operate at a slow speed. A further pair of contacts 42b are connected in parallel with resistance 41 and contacts 28 and are controlled by a relay magnet 42. The object of the contacts 42b is to shunt out the resistance 41

at the start to insure starting of the motor at its slow speed. After the machine has operated through a portion of a cycle, cam contacts L1 close momentarily and complete a circuit from line 38, wire 43, relay magnet 42, contacts L1, wire 44, contacts 40a, to line 31. The consequent closure of contacts 42a will set up a holding circuit for the magnet 42 traceable from line 38, wire 43, magnet 42, contacts 42a, wire 44, contacts 49a, to line 31. Energization of magnet 42 will, of course, open contacts 42b, permitting the inclusion of resistance 41 in the field circuit of motor TM, if the machine is set for tabulating operations.

Inspection of the timing diagram (Fig. 3) will show that the time of closure of contacts L1 occurs after the machine has turned through substantially a third of a cycle so that it will be apparent that operation of the machine for this portion of the cycle will be at the slow speed, regardless of whether contacts 28 have been set open or closed. During the first cycle, the record card C is advanced from the supply magazine to a position where its leading edge is in contact with the upper brushes UB, as previously explained.

Energization of the start relay magnet 39 will effect closure of its contacts 39a to set up a holding circuit for the clutch magnet 29 traceable from line 34, cam contacts P1, magnet 29, relay 48, magnet 39, contacts 39a, wire 45, cam contacts L2 to line 35. Toward the end of this cycle cam contacts L2 break, as indicated in the timing diagram, and the machine will coast through the remainder of the cycle to home position, which will hereinafter be termed the D position, as it is commonly known in the art.

A second machine cycle is now again initiated by depression of the start key to close contacts ST and a second cycle will follow in the same manner as the first. During this second cycle, the first card is advanced to the lower brushes and a second card is fed from the supply magazine. Following this second cycle, the machine may do one of two things. If the automatic resetting switch 46 is open, the machine will stop as before and if the switch is closed, the machine will automatically enter upon a resetting cycle of operations. If the machine stops, the same resetting cycle is initiated by depression of the reset key to close contacts R. It will be pointed out in connection with the group control circuits that the motor control relay 38 is deenergized during the second tabulating cycle just mentioned, so that contacts 38a open and 38b close during the latter part of the cycle.

If switch 46 is closed, the closure of cam contacts L3 toward the end of the second cycle will complete a circuit traceable as follows: from line 35, contacts 39b, switch 46, now closed, cam contacts L3, relay magnet 48, cam contacts P3 to line 34. Closure of contacts 48a will set up a holding circuit for magnet 48 traceable from line 34, contacts P3, magnet 48, contacts 48a, to line 35. At the very end of the cycle, contacts L4 close, permitting the completion of a circuit from line 35, contacts 48a, contacts L4, reset clutch magnet 47, contacts 84c, contacts P3 to line 34. The contacts 84c are controlled by a multi-contact relay magnet 84 (Fig. 2a) which is energized through a circuit extending from line 34, wires 26 and 27, magnet 84, relay contacts 38c, contacts 48b, cam contacts P9, wire 25 (see also Fig. 2), card lever contacts 19, now closed, to line 35.

15 The contacts 38c are controlled by the motor control magnet 38 and are opened when magnet 38 is deenergized due to a change in the group control number, in a manner to be explained. Contacts 48b are opened by the magnet 48 when the latter is energized to initiate a resetting cycle of operations. It is thus apparent that if either of the contacts 38c and 48b are open, magnet 84 is deenergized to permit closing of contacts 84c in the reset clutch magnet circuit. It is thus apparent that during card feeding cycles, contacts 84c are held open and prevent completion of the reset clutch magnet circuit. Magnet 47 will trip the reset clutch mechanism and will cause the closure of the contacts 47a.

16 This will permit completion of the circuit through the reset motor RM which is traceable from line 39, motor RM, magnet 50, wire 51, contacts 47a, wire 52, to line 31. The motor RM will thereupon operate to drive the machine through a reset cycle during which contacts P4 close to short circuit the contacts 47a and maintain the circuit through motor RM, and shortly thereafter, contacts P9 (Fig. 2a) open to break the circuit through the magnet 84 which in turn permits closing of contacts 84c. Later, contacts P8 open to break the holding circuit of magnet 48. Cam contacts P4 open at the very end of the cycle to break the circuit through the motor RM.

20 30 If the machine had stopped after the second tabulating cycle, due to the open position of switch 46, the resetting cycle is initiated by depression of the reset key to close contacts R, which completes a circuit from line 35, contacts 35 L2, wire 46, contacts 39b, contacts R, relay 48, contacts P3, to line 34. Energization of magnet 48 controls the completion of the above traced circuits through reset clutch magnet 47 and the subsequent completion of the circuit through the reset motor RM.

35 40 It has thus far been explained that the initiation of operations of the machine require a first resetting operation, followed by two successively, manually initiated, tabulating cycles, followed by a resetting cycle which is either manually or automatically initiated. At this point, the first card is in readiness to pass and be analyzed by the lower brushes LB and the second card is in readiness to pass and be analyzed by the upper brushes UB and the automatic control mechanism is in readiness to compare the control designation of the cards as they pass through the machine. Following the reset cycle just explained, the machine will stop, if the automatic start switch 53 is open, and further operations of the machine will be initiated by depression of the start key to close contacts ST. If switch 53 had been previously closed, however, the machine will automatically enter upon card feeding and analyzing operations immediately upon completion of the last resetting cycle. This is brought about in the following manner:

45 50 55 60 65 70 75 Relay contacts LCLa will have been closed due to the arrival of the first card at the lower brushes and during the reset cycle just traced, cam contacts P2 closed momentarily at the end of the cycle, thereby establishing a circuit from line 35, contacts 38a, now closed, contacts SP, LCLa and P2, switch 53, start relay magnet 39, contacts 29a, tabulating clutch magnet 29, contacts P1, to line 34. The energization of magnet 29 will, as explained above, cause the machine to enter upon a tabulating cycle of operations, during which the record cards are successively

analyzed and the amounts thereon entered into the accumulators.

Closure of lower card lever contacts 19 completes a circuit from line 35 (Fig. 2), contacts 19, wire 25 (see also Fig. 2a), wire 55 (Fig. 2a), a 5 number of relay magnets LCL, wire 57, to line 34. A number of magnets LCL are provided to distribute the multiplicity of contacts to be controlled. Closure of relay contacts LCLb, together with the closure of contacts LCLa, mentioned above, will complete a holding circuit for relays LCL through cam contacts L6. This circuit is from line 35, contacts L6, contacts LCLb, magnets LCL and wires 57, 27 and 26 to line 34. As long as record cards continue to pass the lower 10 brushes, magnets LCL will remain continuously energized since contacts L6 are timed to be closed during the interval that the card lever contacts 19 open (see the timing chart, Fig. 3). The upper card lever contacts 18 similarly complete a 15 circuit from line 35, contacts 18, magnets UCL, wire 51a, to line 34. The closure of contacts UCLb sets up a holding circuit through cam contacts L5, whose function and timing is the same 20 as that of contacts L6.

The automatic control circuits which keep the machine in operation as long as control designations on successively analyzed cards are the same will now be explained in detail.

A number of double-wound relay magnets are provided, each having a pick-up winding 59 and a holding winding 60. Windings 59 terminate in the jacks 62 and 63 through which the windings may be plug connected in series with the brushes UB and LB. Since the index point positions on the card passing the lower brushes are analyzed concurrently with the analysis of the corresponding index point positions of the following card passing the upper brushes, a perforation occurring in any index point position of both cards will complete a circuit at a time in the cycle of the machine corresponding to the location of the perforation.

The control pick up circuit is traceable as follows: from line 34 (Fig. 2), wires 64 and 65, cam contacts L11, upper brush contact roller 16, designation on the card at the upper brushes, upper brush UB, plug socket 21, plug wire connection to jack 63, winding 59, jack 62, plug wire connection to jack 20, brush LB, designations in 45 the card at the lower brushes, lower brush contact roller 17, circuit breaking contacts 61, lower card lever contacts 19 to line 35.

Energization of winding 59 will close its contacts 59a and 59b, the former setting up a holding circuit for the windings which is traceable as follows: from line 34, wires 64 and 65, cam contacts L12, contact 59a, winding 60, to line 35. Contacts L12 hold the windings 60 energized until nearly the end of the cycle. It is thus apparent that the windings 59 are energized at a differential time in accordance with the value of the controlling perforation and that the windings 60 hold all the selected circuits to keep contacts 59b closed in positions in which agreement occurred between the cards.

In the machine there are provided sixteen sets of windings 59, 60. On the circuit diagram, however, only three are shown, to avoid undue repetition of similar parts. After all the index point positions have been analyzed, the machine tests the setting of the contacts 59b. If there was agreement in all the control columns, the contacts 59b corresponding to those columns will be closed and a series circuit will be traceable

10 through each such contact. The contacts associated with the controlling field of the record card will be grouped together and a plug wire connection made between the jack 22 of the last position into jack 23. This places the contacts 59b (Fig. 2) in the holding circuit. The ultimate object of the group control mechanism is to keep the motor control relay magnet 38 energized, if there is agreement in the control field and to cause deenergization of magnet 38, if there is a break or disagreement in the control field.

Magnet 38 is normally held energized through a circuit set up during the initial resetting cycle of the machine. During this cycle, cam contacts P1, P8 close at substantially the same time, one pair of these contacts being set for accurate making time and the other pair for an accurate break. The circuit will be completed from line 34, wire 64, contacts P1, contacts P8, control relay magnet 66, magnet 67, motor control relay magnet 38, cam contacts L10, wire 68, to right side of line 35. Control relay 66 closes its contacts 66a to establish a holding circuit from line 34, wire 64, contacts 66a, magnet 66 to line 35 as 25 before. This circuit is the control holding circuit and remains energized as long as there is no group change.

While cards of a group are feeding, the contacts 59b provide a shunt circuit around contacts 30 L10. For example, the contacts 59b, when they are closed and when plug connection between jacks 22 and 23 is made, as shown dotted, short circuit contacts L10, the short circuit running from the lower blade of contacts L10 to the lowermost contacts 59b, then to the uppermost pair, plug connection from jack 22 to 23, to the upper blade of contacts L10.

Thus, if at the time contacts L10 open and the 40 control relays have registered agreement between the two cards analyzed, the holding circuit is sustained through the contacts 59b. If, at such time one of the contacts 59b had failed to close, the holding circuit would have been broken, de-energizing relay magnets 66, 67 and the motor control relay 38, causing stoppage of the machine or automatic entry upon a total taking and resetting cycle.

During the subsequent total taking cycles, closure of cam contacts P1 and P8 will again establish the holding circuit and comparison of the successively fed record cards of the next group will take place and card feeding will proceed until there is again a break in either of the circuits.

55 It may here be mentioned that with the automatic reset switch 46 closed, the machine will perform a single cycle of total taking operations and the group control holding circuit will be concurrently reestablished during this single cycle.

60 A switch 70 is provided, which, when closed, permanently short circuits contact L10. If this switch is closed, the control mechanism is inoperative and the holding circuit remains established indefinitely. Various contact devices are included in this control mechanism to delay its functioning until cards have been advanced into the machine in readiness for actual comparison with one another. These devices may be best explained by examining the several starting cycles of the machine.

65 The very first cycle, which is the manually initiated reset cycle, clears the accumulators and operates contacts P1 and P8 to initially establish the control holding circuit and energize motor

control relay 38 so that the starting circuit can be completed. At this time, the lower card lever relay magnets LCL are deenergized as are also the upper card lever relay magnets UCL and their respective contacts LCLg and UCLf short circuit contacts L16 so that during the first card feeding cycle, the opening of contacts 110 is ineffective to break the holding circuit. At the end of this cycle, however, the upper card lever contacts 18 close, causing energization of upper card lever relay magnets UCL and opening of contacts UCLf. As explained above, the machine comes to rest after this first card feeding cycle with the first card about to pass the upper brushes. A second manually initiated cycle then takes place.

During the second card cycle, none of the contacts 59b can be closed since the lower brushes LB, which receive current through the lower card lever contacts 19 do not receive current. Opening of contacts L10 therefore finds no holding circuit for the control relay magnet and the same is therefore interrupted. At this time, the leading card will be at the lower brushes after having closed card lever contacts 19 to supply current to the lower brushes and to cause energization of lower card lever relay magnets LCL, opening the contacts LCLg. The following total taking and resetting cycle will again set up the holding circuits and the machine will proceed with its tabulating operations under the joint control of the contacts L10 and contacts 59b.

When the last card in the machine has passed the upper brushes and is passing the lower, and the upper brushes are making contact on the bare contact roller 16, inspection of the circuit diagram (Fig. 2) will show that circuits will be completed to all the active relays in the same manner as though another card of the same group were passing the upper brushes. This, of course, would indicate an agreement and the group control would not break until the lower card lever contacts opened. Therefore, it is necessary at this time to break the control holding circuit even though the shunt circuit through contacts 59b is closed. This is brought about under control of the upper card lever contacts which open, since no card is at the upper brushes, bringing about the deenergization of the upper card lever relay magnets UCL and permitting opening of contacts UCLe. No shunt circuit can now be established through the contacts 59b so that when the contacts of L10 open the holding circuit will be broken, and the machine will enter upon total taking operations.

Accumulating mechanism

The accumulating mechanism is composed entirely of relay coils and associated contacts. For each denominational order (Fig. 4) of the accumulator, twenty-one relays are provided, two for each digit except the zero digit position which requires three relays for reasons described later. The relays are connected by electrical circuits so as to form a series of sets of relays. Each set comprises a value-corresponding relay paired with a controlling relay and represents an ordinal value or digit position.

In the circuit diagram of the machine (Figs. 2, 2a and 2b), three denominational orders of the accumulator are shown for purposes of illustration. These orders are designated as the units, tens, and hundreds orders. The relay arrangement in each of the orders is similar, so that the structure of the units order as set forth in 75

Fig. 4 is representative of the structure in the other.

In order to condition the accumulator for adding, the analysis of value designations of the first card to pass the lower brushes causes circuits to be completed to adding control magnets 17 (Figs. 2 and 2a) as follows: line 35, card lever contacts 19 now closed, circuit breaker contacts 61, lower brush contact roll 17, through value designations in columns of the card field to be added, corresponding lower brushes LB, plug wire connection from jacks 20 of these lower brushes to jacks 15, adding control magnets 17, to line 34. The magnets 17 energized are maintained in their operated condition by a holding circuit from line 34, magnets 17, contacts 17a, wire 16, cam contacts L33, via wire 83, to line 35. Contacts L33 are timed so as to maintain magnets 17 energized until the end of the adding operation at zero in the cycle (Fig. 3).

First considering entry into the units order of the accumulator (Fig. 4), energization of a magnet 17 related to this order will occur at a differential time in the cycle and cause an entry circuit to be completed as follows: line 36 through the subtraction control contacts 91e, circuit breaker contacts 91, contacts 91b of the units order of accumulator, relay contacts 17b now closed, contacts R10g, value relay contacts R1b, entry control relay coil R11, via conductor 104, to line 35, thus energizing the control relay R11. Contacts R11a will close and thereby establish a circuit to energize value relay R1 from line 34, contacts 91e, circuit breaker contacts 91, contacts 91b, contacts 17b contacts R11a now closed, relay coil R1, to line 35. With relay R1 energized, contacts R11a will close and provide a holding circuit from line 35 via wire 104 to relay coil R1, contacts R1a now closed, resistance r', via wire 105 to contacts R10e or R20d, conductor 106, relay contacts 81a or cam contacts P12, to line 34.

Upon the energization of the value relay R1, the R1d contacts also close. These contacts are of the type known as "make before break" contacts; that is, contacts R1d will become closed before the normally closed contacts R1b open. Thus, when the R1d contacts close, relay R1 is momentarily maintained energized by the circuit which was described for its initial energization. The circuit is slightly altered now, however, by the fact that a resistance r has been brought into the circuit in series with relay coil R11, and the circuit now passes through contacts R1d instead of contacts R1b.

Resistance r is of such a value that it will allow the entry control relay R11 to remain energized and keep contacts R11a closed until the circuit breaker contacts 91 open at the end of the impulse, at which time relay coil R11 is deenergized. Upon entry of the next impulse, resistance r limits the flow of current through coil R11 to a value below that necessary to re-close contacts R11a. So long as resistance r is in series with the now deenergized R11 coil, the contacts controlled by this coil will remain in their normal positions.

Another resistance, designated r', is provided in the holding circuit for relay R1 to prevent a potential holding circuit for the R11 relay coil that would otherwise be established upon the closure of contacts R1a. This potential circuit may be traced as follows: line 35, conductor 104, relay coil R11, resistance r, contacts R1d now closed, contacts R10g, contact R11a also closed,

and then to line 34 through the remainder of the holding circuit for the R1 relay as previously described. The resistance r' , however, being in series with the circuit just described is of such value that, when combined with resistance r will limit the holding current to relay coil R11 and, at the time circuit breaker contacts 91 open after the first impulse, the relay R11 will be deenergized causing its contacts to be restored to normal.

Contacts 11b will provide a circuit from breaker contacts 91 into the accumulator from the time relay 11 is energized until the end of the adding operation, relay 11 being maintained energized by cam contacts L33 as previously explained. It is apparent that after relay 11 becomes energized to condition an accumulator entry circuit, the number of machine cycle points remaining up to "0" will determine the number of impulses from circuit breaker contacts 91 which will be permitted to enter into the accumulator to cause successive energization of the relays. Contacts 91 are of the leaf spring type and are operated from a notched cam (Fig. 2b) which rotates at all times during card feeding cycles and permits the contacts to close at each index point from "9" to "1" for the purpose of providing potential adding impulses for the accumulator. The successive high points of the cam cause the contacts to open shortly after each making point as illustrated in the timing chart (Fig. 3). For illustrative purposes, a specific entry into the units order will now be described.

Assuming, for example, that a value of "5" on the record card is to be entered at "5" in the machine cycle, the adding control magnet 11 associated with the units order is energized as previously described. There are then 5 adding index points from "5" to "0." As the circuit breaker contacts 91 make at "5," "4," "3," "2" and "1" in the machine cycle successive adding impulses are sent to the units order. The action of the first impulse has already been described. The second impulse to enter the accumulator is initiated at "4" in the machine cycle. Contacts 11b are still closed and a circuit is provided to entry control relay R12 as follows: Positive line 34, contacts 91e in the position shown, circuit breaker contacts 91, contacts 91b in the position shown, contacts 11b now closed, contacts R11b in the position shown, contacts R1c now closed, contacts R2b in the position shown, relay coil R12, to line 35. Relay R12 is thus energized and closes its contacts R12a to provide a circuit to energize value relay R2 in a manner similar to that described for the energization of value relay R1. Coil R12 will become deenergized when the circuit breaker contacts open the circuit to this coil at the end of the impulse which caused its energization.

It is apparent from the foregoing explanation that each additional impulse entering the accumulator units order causes the energization of a new value relay, that is, the first impulse caused the energization of relay R1, and the second impulse, relay R2 etc. Such energization of relay R2 was dependent upon the fact that relay R1 remained energized, its R1c contacts being in series with the circuits which energize relay R12 and then relay R2. In like manner when a third impulse enters the counter, it passes through contacts R1c and R2c now closed and results in the energization of a relay R3 in a manner similar to that described for the previous value relays in

the series. Thus, at the end of a fifth impulse, relays R1 to R5 would be energized to represent that "5" had been entered into the units order of the accumulator. The operation of the series of 5 relays for the first nine impulses entered is the same as described above, and thus at the end of the ninth impulse, relays R1 to R9 remain energized. These relays are maintained energized by a circuit through the normally closed R10e and 10 R20d contacts as previously explained. Upon entry of a tenth impulse, however, a somewhat different series of events occur. A circuit to energize entry control relay R20 is provided as follows: line 34, contacts 91e, contacts 11b now closed, contacts R11b, contacts R1c, contacts R12b, contacts R2c, contacts R13b, contacts R3c, etc., to and through contacts R9c, contacts R10b, relay coil R20, to line 35. Relay R20, upon being energized, causes contacts R20a to close and a circuit 15 is thereby completed to the zero value relay designated R10. This circuit is as previously traced through contacts R11b, R1c, R12b, R2c, etc., through contacts R9c, contacts R20a now closed, relay coil R10, to line 35. Contacts R20d, which 20 are in parallel with the R10e contacts, are now opened. Contacts R10a and R10e are of the make before break type and are tied together by means of an insulating portion 102. That is, contacts R10a are designed to close before contacts R10e open. Therefore, upon energization of relay R10, contacts R10a will close, providing a holding circuit for relay R10 from line 35, through relay coil R10, contacts R10a, resistance r' , conductor 103 and cam contacts L31 to line 34. 25 The timing of cam contacts L31 is such as to maintain relay R10 energized until the fourteenth cycle point in the machine cycle, at which time carrying operations will have been completed. After contacts R10a have closed, contacts R10e 30 will open and since contacts R20d are already open as previously described, the holding circuit for the value relays R1 through R9 is now broken, and their contacts are returned to their normal position. 35 Contacts R20d are placed in the circuit to bypass the R10e contacts for the purpose of re-establishing the holding circuit for relays R1 through R9 immediately after it is broken by the opening of the R10e contacts. The deenergization of relay R20 upon the termination of the tenth impulse allows contacts R20d to close and perform their function as above described, so that after the next impulse and succeeding impulses, the value relays successively energized by these 40 impulses will have a holding circuit to maintain them energized in a manner already described. Contacts R10e are held open by the energized R10 relay for an appreciable time which would allow the next impulse to enter the accumulator to energize the R1 relay but would not allow a maintaining circuit for this relay to be established, except for the presence of the R20d contacts which complete the circuit in time to take care of this condition. 45 The re-energization of relays R11 and R1 from the tenth impulse must be prevented. This condition would be likely to occur just after the R20d contacts had re-established the holding circuit for relays R1 to R9, except for the fact that contacts R10g are provided. As soon as relay R10 became energized, contacts R10g opened and prevented the completion of an entry circuit to energize relays R11 and R1. It will be noted a relay K is also provided and connected to the common side of circuit breaker contacts 91 and 50 55 60 65 70 75

91a. Each impulse from the circuit breaker contacts 91 will cause the K relay to be energized by a circuit from line 34 through contacts 97e, circuit breaker contacts 91, common conductor 107, relay coil K, via conductor 108 to line 35. Circuit breaker contacts 91a are used for subtraction operations because when subtracting, as will be explained later, relay 87 is energized and the circuit to energize the K coil goes through contacts 97d and breaker contacts 91a. Once relay K is deenergized, following the opening of contacts R10e, the entry circuit for energizing the accumulator relays may be re-established. This is brought about by the closing of contacts R21b in the following manner: with relay R10 energized when contacts K1 reclose, the relay R21 will be connected in parallel with relay R10 and also become energized. At the time relays K and R20 were first energized, the relay R21 could not pick up because the contacts K1 are adjusted to open before the contacts R20a close, to allow a circuit to be completed to the R10 relay. Relay R21 remains energized until relay R10 becomes deenergized. This condition is obtained by the shunt circuit through R21A provided around the K1 contacts.

It would now be well to summarize briefly the sequence of events which occur upon the entry of a tenth impulse into an order of the accumulator. Relays R1 to 9 will have been energized prior to the tenth impulse. Upon entry of the tenth impulse, relays K and R20 are energized concurrently, but the K1 contacts open before R20a contacts close and relay R10 is energized. The energization of relay R10 drops the relays R1 to 9 and also deenergizes relay R20. When relay K becomes deenergized, relay R21 becomes energized and prepares the accumulator order for the next impulse by closing its R21b contacts.

The foregoing description has shown how a digit representation of "1" to "9" may be entered into the accumulator, and also how, after relays R1 to 9 are energized, the next impulse causes the energization of relay 10, this relay in turn being maintained energized while the accumulator relays R1 to 9 were restored to normal in preparation for new entries in the accumulator.

Whereas the entry of a value into the units order of the accumulator has been described, it would be simply repetition to describe the same for the tens, hundreds and higher orders; that is, adding control magnets 77 associated with the tens, hundreds and higher orders would also be energized at a differential time in the cycle according to value designations on the record card and close contacts 77a to effect impulse entries from circuit breaker contacts 91 and through contacts 77b in a manner similar to that already described.

As is customary in accumulators of the type disclosed, it is necessary to enter 1 into a denominational order when the next lower order passes from "9" to "0." The means provided for doing this is termed a "concurrent carry"; that is, entry of one into one order due to the next lower order having passed from "9" to "0" is concurrent with all other orders. If the order into which the carry entry is made is standing at "9," a passage from "9" to "0" occurs, and one is concurrently added into the next higher order above. Such a condition would occur where, for example, the amount standing in the accumulator was "97" and "3" was the amount to be added. Here, obviously, for the correct result of "100" to be obtained, there must be a double carry, one from the 75

units into the tens order and the other from the tens into the hundreds order.

The circuit arrangement to effect the carry operations will now be explained. As was previously described, upon the units order passing from "9" to "0", the relay R10 became energized and was maintained energized by cam contacts L31. During the carry portion of the cycle, magnet 85 is maintained energized by a simple circuit from line 34, wires 26 and 27, cam contacts L34, carry magnet 85, to line 35. The carry time in the cycle has been shown as the 13th cycle point. At this time carry magnet contacts 85a are closed and when cam contacts L32 close a circuit is completed as follows: line 34, cam contacts L32 now closed, contacts R10c now closed, carry control contacts 85a now closed, to the tens order of the accumulator. If the tens order of the accumulator were standing at some value between "1" and "8" inclusive, one will be added into this order by means of the customary circuit and cause the energization of the next higher value relay. If, however, the tens order was standing at "9", a circuit would be completed as previously traced, and also from the 85a contacts through the R10c contacts, R9e contacts now closed, further contacts 85a now closed, to the hundreds order of the accumulator. It will be noted that carry magnet 85 is of the multi-contact type and a pair of contacts 85a are located between successive orders of the accumulators.

Assume that the tens order has just passed from "9" to "0" previous to the carry. A circuit will then be completed (Figs. 2a, 2b) from line 34, contacts L32, contacts R10c of the tens order now closed, contacts 85a, now closed, to the hundreds order. It is necessary to prevent the R10c contacts in this case from sending in an extra impulse to the hundreds order when they close, since these contacts are connected in the carry circuit. The deenergization of relays R1 to 9 of the tens order, which occurred upon the energization of relay R10 causes contacts R9c to open, but contacts R10c close previous to the opening of the R9c contacts and therefore the entry impulse will not be broken into two parts. The R10c contacts are provided to prevent carrying from a lower order into the next higher order when a carry impulse into the lower order has just sent the counter from "8" to "9". Contacts R9e will be closed at this time, but the R10c contacts will be open and prevent an incorrect carry.

Subtraction may be performed by this accumulator and may be controlled for this purpose in various ways, one of which is the so-called "X" selection method which has already been briefly described. The "X" position on the record cards is the next index point after the "0" position and is analyzed at the 11th cycle point in the card feed cycle. For detailed explanation of "X" selection control from record cards, reference should be made to the previously mentioned U. S. Patent #1,976,617. It will, of course, be understood, that the accumulator may be arranged to subtract every amount entered therein, but the "X" selection method is suggested as a demonstration of greater flexibility of application in regard to modern electrical accounting machines and the work which these machines are called upon to perform.

Assuming the machine is plugged so that "X" cards are to be subtracted, when an upper brush senses the "X" designation on the card, a circuit is established to control the accumulator for sub-

tractive entry during the following cycle as that same card passes the lower brushes. This circuit is as follows: line 34, wires 64 and 65, cam contacts L14, upper brush contact roll 16, value designation of the card, upper brush UB in the corresponding column, plug hub 21, plug wire connection to plug hub 94 (Fig. 2a near upper left corner), cam contacts L23 now closed, contacts UCLd now closed, relay coil 95 to line 35. Relay 95 is thus energized and the 95a and 95b contacts will close; the former providing a holding circuit through cam contacts L25 back to line 34 and the latter causing relay coil 97 to become energized when cam contacts L37 close by the following circuit: line 34, cam contacts L25 now closed, cam contacts L31 now closed, contacts 95b, relay coil 97, to line 35. Cam contacts L15 will hold relay 97 energized from the time relay 95 becomes deenergized in one cycle until past the adding portion in the next cycle.

With relay 97 energized, relay contacts 97d and 97a close to establish an entry circuit to the accumulator from line 34, contacts 97d now closed, circuit breaker contacts 91a, contacts 97a now closed, contacts 11c into the accumulator and then to line 35. Breaker contacts 91a send a succession of impulses over this circuit commencing at the beginning of the subtraction cycle. Each impulse energizes one further value relay in each of the denominational orders of the accumulator which are plugged for entry. When a value designation in the card is encountered by a lower brush in the corresponding column, the feeding of impulses into the accumulator order to which this column is plugged is abruptly halted because the adding control magnet 11 associated with that order becomes energized, thereby opening contacts 11c to break the entry circuit. The making time of breaker contacts 91a is slightly delayed as compared with breaker contacts 91 (Fig. 4). This condition is required so that when a value designation is encountered, the entry circuit to the corresponding order of the accumulator may be broken before another subtractive impulse is entered into the accumulator. Also, under the condition in which "9" is being subtracted, it is necessary to prevent any impulses from entering the accumulator.

By the above circuits, then, if "5" was the value to be subtractively entered into one order of the accumulator, breaker contacts 91a would send out an impulse slightly after each of the cycle points "9", "8", "7", and "6". Then at "5" in the cycle the encountering of the "5" designation of the card in the corresponding column, adding control magnet 11 becomes energized as explained above to break the entry circuit by opening its contacts 11c. At this time four impulses have actually been entered in this order. Thus, instead of actually subtracting "5", the same result has been accomplished by the entry of its complement number of impulses. In the units position an extra impulse is necessary because the complements in this position must add up to ten. This extra impulse, known as "the elusive one" is provided in a manner to be described presently.

Subtraction occurs in all orders concurrently and in a similar manner, and the final result is obtained following the carry time in the cycle. It is during this time that the so-called "elusive one" is entered into the units order. The "elusive one" circuit becomes effective only in the cycle following the energization of relay 97. This circuit may be traced as follows: line 34, wires 26

and 27, cam contacts L35 now closed, contacts 97f now closed, relay coil 86, to line 35. Coil 86 is maintained energized until after the carry operation in this same cycle by a circuit from line 34, wires 26 and 27, cam contacts L36 now closed, contacts 86a now closed, coil 86, to line 35. With relay coil 86 energized, the contacts 86b are also closed (Fig. 2b), and at the carry time in the cycle contacts 85b are also closed to provide an entry circuit into the units order of the accumulator as follows: line 34, relay contacts 85b now closed, contacts 86b now closed, to units order of the accumulator, through next successive set of accumulator relays in the series to line 35.

Total printing circuits

Total printing of amounts standing in the accumulator is provided and is under the control of relay 14, total print emitter 93, and read-out contacts associated with each of the value relays. The circuits are so arranged that read-out is effected from the last-operated relay in each denominational order of the accumulator. Totals are printed during a reset cycle which, as previously described, may be initiated manually by the depression of the reset key to close contacts R, or, if the machine is preset accordingly, totals may be taken automatically after the feed has been halted at the end of a group of cards. The total print emitter 93 is provided with a pair of brushes 180° apart which are arranged to be driven by the reset mechanism so as to rotate through one-half a revolution on each reset cycle.

As either of the brushes passes the segment spots on the emitter, circuits are completed to the total print magnets in the event that values corresponding to those segment spots are standing in the accumulator readout mechanism. This type of emitter is of common knowledge in the tabulating art.

A total switch 78 is provided and is manually settable in one of two positions; an "off" position which is the position shown in the diagram (Fig. 2a) or a "total" position in which brushes 80 bridge contacts 82 and brushes 79 bridge contacts 88. In order to complete circuits to print magnets 87 it is necessary to energize multi-contact relay magnet 14, and to effect the energization of this relay it is necessary to set switch 78 to the "total" position to complete a circuit as follows: line 35, relay magnet 14, contacts 84a, switch 100, contacts 82, brush 80, cam contacts P6 now closed, wire 26 to line 34. With magnet 14 energized, contacts 74b close and circuits may be completed to print magnets 87 as follows: line 34, print magnet 87, contacts 74b now closed, through normal read-out contacts R9g, R8g, R1g, etc. to the shifted read-out contacts of the last-operated value relay in the order, emitter 93, circuit breaker contacts 58 (Fig. 2a), switch 56, to line 35. That is, for example, if "6" is the value standing in the units order of the accumulator as represented by the fact that relay R6 is the last-operated relay in that order, read-out contacts R9g, R8g, and R1g are closed as shown, but the read-out contacts associated with relay R6 are shifted so that contacts R6g are open and contacts R6f are closed. This permits a read-out circuit at the "6" time in the total cycle from line 34, print magnet 87, contacts 74b, now closed, contacts R9g, R8g and R1g, contacts R6f, now closed, emitter 93, circuit breaker contacts 58, switch 56, to line 35. Switch 56 is provided so

that all total printing may be suppressed by manually setting this switch to its "off" position to prevent the establishing of the above circuit. Whenever total printing is desired, it is necessary to have this switch in the position shown in the diagram (Fig. 2a).

If at the end of a series of subtractions and additions of amounts into an accumulator, a complementary amount remains therein, provision is made whereby total printing may be prevented. This is effected by shifting switch 100 to its dotted line position so that the circuit to energize relay 74 contains in this case the series contacts R9m of the hundreds order, since this is the highest order of the accumulator being used. It must be assumed that this order is being used for balance control only, i. e. not for adding. A "9" standing in this position indicates a complementary amount and will prevent the energization of relay 74. If any other value is standing in the hundreds order, the relay 74 will be energized by a circuit from line 35, relay magnet 74, contacts 84a, contacts R9m, switch 100 in dotted line position, switch 78, cam contacts P6 now closed, to positive line 34.

A simple electrical resetting means is provided for clearing the accumulator. On the reset cycle, relay magnet 50 is energized, as has been already explained under the heading of "General machine circuits" so that contacts 50a are closed, and, with switch 78 set to its "total" position a circuit is completed to energize relay 81 as follows: line 35, contacts 50a now closed, relay coil 81, contacts 88 and brushes 79 of switch 78, conductor 26, to line 34. The energization of relay coil 81 causes contacts 81a to open (Fig. 2b) and remain open during the reset cycle. These contacts are in the circuit which maintains all the value relays energized. When contacts 81a open, however, the value relays are not deenergized immediately because cam contacts P12 by-pass these contacts until a point later in the cycle after the totals have been read-out. When contacts P12 open all the accumulator relays are instantaneously deenergized, thus clearing the accumulator of old totals standing therein and reconditioning the same for new entries so that new totals may be ascertained. It will be noted that the actual resetting of the accumulator is accomplished entirely by electrical means and none of the customary mechanical resetting structure is required.

Summary of operation

It has been shown that the accumulator comprises a plurality of orders, each of which has for its structure a series of sets of companion relays and interconnecting circuits. Multiple timed impulses are fed into the accumulator and successively energize a plurality of relays therein. On adding, the number of impulses entered in any one order is equal to the value of the digit represented by these impulses. On subtracting, a complement number of impulses are automatically entered to energize successively further relays in the series. Each impulse entered into an order causes the energization of an entry control relay which in turn effects the energization of its companion value relay. When any order passes from "9" to "0", relay representing digits "1" to "9" become concurrently and automatically deenergized. Electrical carry means is provided so that, upon one order passing from "9" to "0", a carry impulse is entered into the next higher order. Total taking means is provided and con-

sists of additional contacts controlled by the value relays, and an emitter for imparting impulses to the print magnets at a differential time in the total cycle. Resetting means for the accumulator consists of contacts which open during the resetting cycle and break the holding circuits to all accumulator relays, thereby clearing the accumulator of totals that were standing therein.

10 While there has been shown and described and pointed out the fundamental novel features of the invention as applied to a single modification, it will be understood that various omissions and substitutions and changes in the form and 15 details of the device illustrated and in its operation may be made by those skilled in the art without departing from the spirit of the invention. It is the intention therefore to be limited only as indicated by the scope of the following 20 claims.

What is claimed is:

1. In a cyclically operating accounting machine controlled by a record having value designations differentially located thereon in accordance with the magnitude of the digit values, in combination, means for analyzing said record while in motion for said value designations during a cycle, an impulse circuit including circuit breaker contacts capable of causing intermittent energization of the circuit to initiate a predetermined number of impulses in succession corresponding to the highest digit value within said cycle, a control relay including contacts in said circuit operated under the control of the analyzing means upon analysis of one of said value designations for conditioning the circuit for initiation of impulses by the circuit breaker contacts at a differential time in the cycle depending on the location of the latter value designation on the record, whereby a succession of impulses dependent in number upon the location of said value designation is effectively initiated during the remainder of the aforesaid cycle, a series of pairs of relays, each pair including an entry control relay and a value manifesting relay, means for directing the first of said succession of impulses to an entry control relay of one of the pairs of relays in the series, means controlled by the latter relay upon receiving an impulse for operating the companion value relay, means controlled by said value relay upon becoming energized for maintaining itself in an operated condition and to cause deenergization of the operated entry control relay upon interruption of the first impulse, and means controlled by the latter entry control and value relays for routing the next impulse to the next entry control relay, whereby the pairs of relays are operated in progression from one digit value position to another until a number of progressive operations are performed corresponding to the number of impulses initiated during the cycle in accordance with the magnitude of the analyzed value.

2. In an accounting machine controlled by a record having digit value representations thereon, in combination, value sensing means for sensing said digit values, an impulse circuit including means capable of emitting a predetermined number of impulses corresponding to the highest digit value, means controlled by the sensing means in accordance with the magnitude of a sensed value for rendering said impulse circuit effective for the emission of a succession of impulses corresponding in number to the magnitude of said sensed value, an ordinal series of

value relays and an individual entry control relay accompanying each of said value relays, one of the entry control relays being responsive to the impulse circuit so as to be operated by the first impulse, means controlled by the latter entry control relay upon operation thereof for causing its related value relay also to become energized by the first impulse, means controlled by the latter value relay upon becoming energized to maintain itself in an operated condition and to cause deenergization of the operated entry control relay upon interruption of the first impulse, means controlled by the latter value relay and entry control relay for routing succeeding impulses from the impulse emitting means to other entry control relays for energizing said other entry control relays and their related value relays in succession, whereby a progression of successive operations of said relays of one ordinal value after another is continued a number of times corresponding to the magnitude of the sensed value.

3. In an accounting machine controlled by a record having digit value representations differentially located thereon according to the magnitudes of the digit values, in combination, analyzing means for analyzing said value representations on said record, a normally ineffective impulse circuit including repeatedly operating contacts capable of closing said circuit intermittently to initiate impulses, means controlled by the analyzing means upon analysis of a value representation for rendering said impulse circuit effective for the initiation by said contacts of a succession of impulses dependent in number upon the location of the analyzed digit value, an ordinal series of value relays and an individual entry control relay accompanying each of said value relays, one of the entry control relays having initial connection with the impulse circuit so as to be operated by the first impulse, means controlled by the latter entry control relay upon operation thereof for causing its related value relay also to become energized by the first impulse, means controlled by the latter value relay upon becoming energized to maintain itself energized and to effect deenergization of the operated entry control relay upon termination of the first impulse, means controlled by the latter value relay and entry control relay for routing succeeding impulses originating as an incident to the operation of the contacts of the impulse

5 circuit to other entry control relays for energizing said other entry control relays and their related value relays in succession, whereby a progression of successive operations of said relays of one ordinal value after another is continued a number of times corresponding to the magnitude of the analyzed value.

4. In a cyclically operating accounting machine controlled by a record having digit value representations differentially located thereon according to the magnitude of the digit values, in combination, analyzing means for analyzing said record while in motion for said value representations, an impulse circuit including circuit breaker contacts capable of causing intermittent closing of said circuit so as to generate a number of impulses equivalent to the highest of said digit values during a cycle, means controlled by the analyzing means upon analysis of a value representation for rendering said impulse circuit effective at a differential time for the generation of a succession of impulses dependent in number upon the location of the analyzed value upon repeated operations of the circuit breaker contacts during the remainder of the cycle, an ordinal series of value relays and an individual entry control relay operatively connected to each of said value relays, one of the entry control relays being included in the impulse circuit for the initial impulse so as to be actuated thereby, 10 means controlled by the latter entry control relay upon actuation thereof for causing its related value relay also to become energized by the first impulse, means controlled by the latter value relay upon becoming energized to maintain itself energized and to effect deenergization of the operated entry control relay upon termination of the initial impulse, means under control of the latter value relay and entry control relay for directing succeeding impulses originating as 15 an incident to the operation of the circuit breaker contacts during the remainder of the cycle to other entry control relays for energizing said other entry control relays and their related value relays in succession, whereby a progression of successive operations of said relays of one ordinal value is continued a number of times dependent upon the number of impulses actually generated during the cycle which correspond in number 20 to the magnitude of the analyzed value.

50 JAMES W. BRYCE.
